Primary Examiner — Mitchell Siegel(74) *Attorney, Agent, or Firm* — Techmarka Law Corp.; Martin R. Greenstein**(57) CLAIM**

The ornamental design for a refrigerated cooler, as shown and described.

DESCRIPTION

FIG. 1 is the front view of the refrigerated cooler according to the present invention;

FIG. 2 is a back view of the refrigerated cooler as shown in FIG. 1;

FIG. 3 is a top view of the refrigerated cooler as shown in FIG. 1;

FIG. 4 is a right side view of the refrigerated cooler as shown in FIG. 1;

FIG. 5 is a left side view of the refrigerated cooler as shown in FIG. 1; and,

FIG. 6 is a front left side perspective view of the refrigerated cooler as shown in FIG. 1.

1 Claim, 6 Drawing Sheets**FIG. 1**

FIG. 2

FIG. 3

FIG. 4

FIG. 5
